UNITED STATES PATENT OFFICE.

GEORGE E. MIGNON, OF SHORT HILLS, NEW JERSEY, ASSIGNOR TO PAUL H. SMART, OF NEW YORK, N. Y.

VANITY CASE.

Application filed October 5, 1923. Serial No. 666,784.

To all whom it may concern:

Be it known that I, GEORGE E. MIGNON, a subject of the King of Great Britain, and a resident of Short Hills, in the county of 5 Essex and State of New Jersey, have invented a new and Improved Vanity Case, of which the following is a description.

My invention relates to a vanity case adapted to hold face powder and rouge, for 10 example.

More particularly the invention relates to a vanity case employing a spring-pressed follower below the face powder acting to force the powder upwardly as fast as it is 15 consumed.

The main object of my invention is to provide a novel powder and rouge containing and dispensing assemblage involving a refill unit, the bottom of which constitutes a 20 follower for the powder and is adapted to be engaged by the spring provided for the purpose in the container at the bottom of said container.

The nature of the invention and its distinguishing features and advantages will 25 clearly appear as the description proceeds.

Reference is to be had to the accompanying drawings forming a part of this specification, it being understood that the drawings are merely illustrative of an example of 30 the invention.

Figure 1 is a longitudinal vertical section of a vanity case embodying my invention;

Figure 2 is a plan view;

Figure 3 is a vertical section of the refill cartridge in the form in which it is vended ready for placing in the body of the vanity case.

In carrying out my invention in accordance with the illustrated example, the vanity case is formed with a container body 10. The container 10 is formed with a transversely extending vertical partition 11 dividing the container into a main compartment 12 for 40 receiving the powder refill cartridge and a compartment 13 to accommodate a refill cartridge of rouge in powder form.

In the illustrated example advantageously the bottom 14 of the container is common 50 to the two compartments 12, 13, said bottom being hinged at one end as at 15 and provided at the other end with suitable fastening means such as a catch adapted to en-

gage any approved latch member 17. Similarly, the cover 18 is common to both compartments and is hinged at one end as at 19.

In accordance with my invention I provide a refill cartridge 20 to contain face powder indicated at b. The refill cartridge 20 has a loose bottom 21 constituting a follower 60 for the powder b. Said bottom 21 rests on inturned supporting means provided at the bottom of the body of the container and preferably in the form of a flange 22 directed laterally inward from the lower edge of the 65 side walls of the body. At the top of the refill cartridge is a perforated disk 23 having an upturned flange 24 fitting within the container 20 whereby the disk 23 occupies a depressed position to accommodate a powder puff c between the disk 23 and the cover 18. The lower edge of the body of the container 20 is open within the flange 22, whereby to obtain clearance for a coil spring 24, the lower end of which is secured to the bottom 75 11 of the container 10. In the illustrated form of the invention the container 10 is provided with an angle piece 25 at the top above the space for the refill cartridge, 20, and retains the cartridge 20 in position as 80 well as resisting the upward pressure exerted against the disk 23 by the pressure exerted on the powder through the follower bottom 21 of the refill cartridge.

In practice a refill cartridge is placed in 85 the compartment 12 with the upper edge of the cartridge against the angle piece 25. The closing of the cover 11 will press the spring 24 against the under side of the follower bottom 21 of the cartridge thereby 90 raising said follower bottom from its rest on the flange 22. The powder will thus be forced to some extent through the perforations of the disk 23 to be taken up by the powder puff c. As the powder is consumed 95 it will be continuously fed to the disk by reason of being under pressure as described and thus the complete contents of the cartridge can be consumed. When the cartridge 20 is empty it is removable as a unit including its follower bottom 21 and its disk 23 and is then replaced by a filled cartridge unit having a charge of powder b and constituting a vendable article to be purchased by those possessing a vanity case 10 having the 100 spring 24. The same applies to the rouge

as to the powder, a spring 26 being provided on bottom 11 beneath the follower 27 on which the rouge *a* is supported.

I would state in conclusion that while the 5 illustrated example constitutes a practical embodiment of my invention, I do not limit myself strictly to the exact details herein illustrated, since, manifestly, the same can be considerably varied without departure 10 from the spirit of the invention as defined in the appended claims.

Having thus described my invention, I claim:

1. A vanity case, and a powder containing 15 cartridge therefor adapted to be made up as a refill, said vanity case presenting an opening through which the cartridge may be entered and removed, a closure on the vanity case for said opening, and a spring in said 20 vanity case beneath the cartridge, said cartridge having an opening in the bottom thereof, a movable bottom constituting a follower for the powder, said follower seating on said spring and subject to the pressure 25 thereon for upward movement, and a perforated disk at the top of the cartridge through which disk powder may exude under pressure of the spring-pressed follower, said vanity case having stop means at the top 30 to retain the cartridge.

2. As a new article of manufacture, a vanity case having an opening, a powder containing cartridge adapted to constitute a refill, said cartridge being enterable and removable through said opening of the case, 35 a closure for said opening, a perforated disk in said cartridge at the top, a follower bottom in the cartridge, retaining means on the cartridge beneath said bottom, and a spring 40 in the bottom of said case beneath said follower bottom and exerting pressure on the latter.

3. As a new article of manufacture, a vanity case having an open bottom and having 45 an angle piece at the interior of the casing at the top, a closure for the said open bottom, a powder-containing cartridge insertable and removable through said opening of the case, a perforated disk in said

cartridge at the top, a bottom in the 50 cartridge movable vertically to constitute a follower for the powder, an internal flange on the cartridge below said bottom, and a spring on said closure and bearing against the bottom of the cartridge to exert upward 55 pressure thereon.

4. As a new article of manufacture, a vanity case having an opening, and a powder cartridge insertable and removable through said opening, said cartridge having a bottom movable upwardly in the cartridge as a follower for the powder and having a perforated disk therein at the top, said cartridge with its said follower bottom and its said disk being insertable and removable 60 as a unit through said opening in the case; together with a spring beneath said bottom and exerting upward pressure thereon.

5. As a new article of manufacture, a vanity case having an opening therein, and 70 a refill powder cartridge insertable and removable through said opening, said cartridge having a follower bottom therein.

6. As a new article of manufacture, a refill powder-containing cartridge for vanity cases, said cartridge having a follower bottom 75 therein, and a perforated disk at the top thereof and adapted with its said bottom and disk to be inserted as a unit in a vanity case.

7. As a new article of manufacture, a powder-containing cartridge constituting a refill for vanity cases, said cartridge comprising a body having the walls thereof at the lower edge inturned, a follower bottom 85 resting on said flange, and a perforated disk in said cartridge at the top.

8. A vanity box, a loose powder container in said box and open at its upper end, a 90 slideable bottom for said container, a screen closing the upper end of said container, and a spring for applying pressure to yieldingly advance said bottom, said box having means to prevent accidental upward movement of the container under the power of said 95 spring.

GEORGE E. MIGNON.
